UNITED STATES PATENT OFFICE.

JOHN W. McAULIFFE, OF PELHAM, NEW YORK.

SANITARY PACKAGE OF INDIVIDUAL SEALED CARTONS.

1,338,315.

Specification of Letters Patent. Patented Apr. 27, 1920.

Application filed March 28, 1919. Serial No. 285,849.

To all whom it may concern:

Be it known that I, JOHN W. McAULIFFE, a citizen of the United States, residing at town of Pelham, county of Westchester,

5 State of New York, have invented a certain new and useful Improvement in Sanitary Package of Individual Sealed Cartons, and declare the following to be a full, clear, and exact description of the same, such as 10 will enable others skilled in the art to which it pertains to make and use the same, reference being had to the accompanying drawings, which form a part of this specification.

15 My invention has for its object to produce a simple, neat and attractive means of packaging individual units or multiples of commodities of various kinds in such a way that each unit or multiple thereof will be 20 sealed in an individual container, the separation of which from the package will not in any way affect the remaining containers.

A further object of the present invention is to produce a simple and novel package 25 of small individual containers of such size that the package may conveniently be carried about in a person's pocket and become gradually reduced in size through the removal of one container after the other.

30 While my invention is applicable to other uses, it is particularly useful for the purpose of packaging cigars, cigarettes or tobacco, all of which should not only be protected against contamination until they are 35 about to be consumed, but which should be sealed up in such a way that they will retain their initial moisture. By placing each individual cigar or cigarette or each individual pipeful of tobacco or a few pipefuls

40 of tobacco in individual sealed cartons suitably constructed to retain the moisture of the tobacco and assembling a number of individual cartons in a package in the proper way, a smoker is enabled to secure

45 a package convenient to carry in the pocket and containing a plurality of cigars, cigarettes or pipefuls of tobacco, from which package individual units may be removed without affecting the remainder of the 50 units; the unconsumed cigars, cigarettes or tobacco being preserved in their original state and the package becoming progressively smaller with the removal of each unit and thus making it unnecessary to carry 55 about a bulky box or the like after its contents have been partly consumed.

Therefore, viewed in one of its aspects, my invention may be said to have for its object to produce a simple and novel package comprising a multiple of sealed individual units of smoking material.

The various features of novelty whereby my invention is characterized will herein-after be pointed out with particularity in the claims; but, for a full understanding 65 of my invention and of its objects and advantages, reference may be had to the following detailed description taken in connection with the accompanying drawing, wherein:

70 Figure 1 is a perspective view of a group of individual sealed cartons placed side by side and ready to be formed into a single package;

Fig. 2 is a perspective view of the package formed, the ends of some of the labels by which the cartons are secured together having not yet been completely attached;

Fig. 3 is a view of a fragment of one of the end labels, for example, the bottom 80 label, employed in Fig. 2;

Fig. 4 is a longitudinal section through one of the individual cartons illustrating its use as a container for a single cigar or cigarette;

Fig. 5 is a view similar to Fig. 4 showing the use of the carton as a container for one or more individual charges of pipe tobacco;

Fig. 6 is a longitudinal section through the upper end of one of the cartons on a somewhat larger scale, illustrating one form of a cap or closure that may be employed;

Fig. 7 is a view similar to Fig. 6 illustrating a means for insuring that the carton will be completely sealed; and

Fig. 8 is a view similar to Figs. 6 and 7, showing a modified closure for one of the cartons.

100 Referring to the drawing, 1, 2, 3, 4 and 5 represent a series of small cartons or containers, preferably square or rectangular in cross section. Any desired number of these cartons or containers are placed side by side as shown in Fig. 1, and they are then secured into a single package by means of labels which preferably cover all six faces of the package; the labels being perforated or otherwise weakened in the 105 planes of contact between the cartons or containers, so that an individual unit may

readily be separated by simply tearing the label or labels along the weakened lines.

In the arrangement shown, three labels are employed in making up the package; 5 there being a bottom end label, 6, a top end label, 7, and a label, 8, which is wrapped around the other four sides of the group of cartons. The labels are perforated, scored or otherwise weakened along lines indicated 10 by the dotted lines, 9, each of which lies in the plane of contact between two cartons or containers. The weakened lines may conveniently be formed by making small perforations as indicated at 10 in Fig. 3.

15 By placing the cartons or containers in a single layer, each carton will be held on four sides by the labels after the first unit has been separated from the package, so that the remaining partial package will not lose 20 its shape; the result being a simple flat package which simply becomes smaller as the contents of the package are consumed.

Each little carton may, and preferably does, contain a single cigar, cigarette or 25 pipeful of tobacco; but it will of course be understood that there may be more than one cigar, cigarette or pipeful of tobacco in each carton.

Each carton is made of any suitable material which, where tobacco products are concerned, will preferably be impervious to air and moisture, so that the tobacco will not become dry. One end of each carton may be sealed in the process of manufacturing the carton, while the other end should be provided with a closure which can be made tight. In the arrangement shown in Figs. 4, 6 and 7, the upper end of the carton is closed by a cap, 10, fitting over the same, 35 the parts being so made that the outer side faces of the cap will be flush with the outer surfaces of the carton. If desired, a small strip, 11, may be gummed or pasted around the joint between the cap and the body of the carton as illustrated in Fig. 7. However, the member 11 is intended simply to be 45 indicative of a label of any kind and size which may be applied to each individual carton.

50 In Figs. 5 and 8 there is shown a different form of closure consisting of flaps, 12 and 13.

If desired, a lifting device may be placed in each carton to permit the contents to be 55 readily withdrawn. In Fig. 5 there is illustrated a device of this kind comprising a

false bottom or tray, 13, lying underneath the contents of the carton and having connected thereto a cord or other member, 14, which leads to the top so that it may be 60 grasped when the carton is opened.

While I have illustrated and described with particularity only a single form of my invention with slight modifications, I do not desire to be limited to the exact structural 65 details thus illustrated and described; but intend to cover all forms and arrangements which come within the terms employed in the definitions of my invention constituting the appended claims. 70

I claim:

1. A package comprising a series of sealed closed cartons lying side by side to form a single broad flat layer, a label extending around four of the sides of said 75 layer including the two broad faces, and additional labels extending across the remaining two sides of said layer, each label being pasted to each of the cartons, and each label being weakened along lines in the 80 planes of contact between the cartons.

2. A series of long rectangular sealed cartons arranged side by side in a single broad flat layer, and labels extending across and covering all six sides of said layer and 85 secured to each carton to form a strong flat package, said labels being weakened along lines in the planes of contact between said cartons.

3. A series of long sealed cartons of small 90 cross-sectional area arranged side by side in a single broad flat layer, labels extending across at least those sides and edges of said layer which show lines of separation between said cartons and secured to each carton, said labels being weakened along said lines. 95

4. A series of long cartons of small cross sectional area lying side by side in contact with each other to form a single broad flat 100 layer, each of said cartons being closed at one end and having a cap on the opposite end, a sealing member covering the joint between each of said cartons and its cap, and label means covering the surfaces of 105 said layer and pasted to all of the cartons, said labeling means being perforated along the planes of contact between the cartons.

In testimony whereof I sign this specification.

JOHN W. McAULIFFE.
